A. J. MARSHALL.

PLOW.

APPLICATION FILED MAY 29, 1918.

1,307,408.

Patented June 24, 1919.

UNITED STATES PATENT OFFICE.

ANDREW JACKSON MARSHALL, OF RICHMOND, TEXAS.

PLOW.

1,307,408.

Specification of Letters Patent. Patented June 24, 1919.

Application filed May 29, 1918. Serial No. 237,283.

To all whom it may concern:

Be it known that I, ANDREW JACKSON MARSHALL, a citizen of the United States, residing at Richmond, in the county of Fort Bend and State of Texas, have invented certain new and useful Improvements in Plows, of which the following is a specification.

This invention relates to improvements in plows and it is the principal object of the invention to provide a plow capable of being adjusted to cause engagement thereof with the earth at varying depths such as may be desired, thus, rendering the same useful in the ordinary surface cultivation of earth and in the sub-soiling of the same.

Another and equally important object of the invention is to provide a novel form of support for the earth working element whereby the angular positioning thereof can be readily changed.

The foregoing together with additional advantageous details and arrangements of parts of the preferred embodiment of my invention will be clear from the specific description hereinafter contained, when read in connection with the accompanying drawings forming part hereof, wherein said embodiment of the invention is illustrated for the purpose of facilitating a full understanding of the present improvements.

In the drawings:

Figure 1 is a side elevation of the improved plow having parts thereof broken away, and

Fig. 2 is a vertical transverse section therethrough.

Having more particular reference to the drawings, in connection with which like reference characters will designate corresponding parts throughout the several views, 1 represents the beam of the improved plow and 2 the handle members thereof, said handle members of course being secured to the intermediate portion of the beam by a bolt or like fastening device indicated at 3. A clevis or other form of draft connection 4 is secured to the forward end of the beam 1 and serves for an obvious purpose. As will be noted, the rear portion of the plow beam 1 is curved upon itself as at 5 whereby to receive a standard 7 having rollers 8 journaled in the upper and lower ends thereof and adapted for engagement with the curved surfaces of the portions 5 of the beam. The lower end of the standard is curved upon itself as at 9 in order that a suitable form of

earth working element 10 can be secured thereto and is apertured to permit the pivoting of a connecting shoe 11 thereto, while the upper end of the standard is apertured 60 and is pivotally engaged by one end of a connecting rod 12, having a plurality of openings therein, this connecting rod extending into pivotal engagement with an adjusting lever 13 mounted on a toothed segment 65 14 secured to the rear portion of the beam 1 in a suitable manner and carrying the usual spring pressed slideable locking pawl 15 whereby the same can be locked in adjusted positions. In this connection, it is 70 to be noted that the handle portion of the lever 13 is arranged at a point convenient to an operator and consequently, adjustment of the same can be quite readily effected.

A bracket arm 17 is secured to the rear 75 end of the beam 1 and extends therefrom and serves to pivotally support the upper end of a bar 18 which as will be noted is formed with a series of openings 19, while the lower end thereof is pivotally connected 80 at 20 to the adjacent end of the connecting rod 11.

A bracing arm 21 is provided and has one portion thereof secured to the under side of the rear end of the beam 1 while the lower 85 end thereof is engaged with the curved portion 9 of the handle arm 6.

In using my improved plow, to adjust the earth working element 10, it is only necessary to lock the adjusting lever 13 over the 90 segment 14, such movement, obviously moving the upper end of the standard 6, which by reason of its slideable or movable connection with the curved portion 5 of the plow beam will cause the proper adjustment of 95 the earth working element, it of course being borne in mind that the lower end of the standard is pivotally connected to the shoe 11 which is in turn engaged with the bar 18. Obviously, in this way, the earth working 100 element 10 can be adjusted to different angular positions for the ordinary surface cultivation of soil or for sub-soiling operations, such as conditions or preference may dictate. Should it be desired, the bar 18 can 105 be adjusted with relation to the bracket arm 17 to cause the arrangement of the earth working element 10 at greater or less acute angles.

Manifestly, the construction shown is capable of considerable modification and such modification as is within the scope of 110

my claim, I consider within the spirit of my invention.

I claim:

5 In a plow, a beam having one portion thereof formed to provide a curved bearing surface, a standard having one portion thereof engaged about the beam adjacent said bearing surface, rollers carried by the standard engageable with the curved upper and lower surfaces of the curved portion of the standard, a bracing arm fixedly secured at one end to one end of the beam and pivoted at its remaining end to the lower portion of

said standard, a rearwardly disposed shoe pivoted at one end to the lower end of the 15 standard and extending rearwardly of the beam, a bar pivoted to the free end of said shoe and pivotally connected at its remaining end to the adjacent end of said beam, an operating lever mounted on the upper portion of said beam at its rear end, and means for effecting connection between said operating lever and the upper end of said standard. 20

In testimony whereof, I affix my signature hereto.

ANDREW JACKSON MARSHALL.
